Brake Shoe Tool

Lee Austin Simmons, Fortuna, Calif.

Application August 5, 1957, Serial No. 47,227

Term of patent 14 years

(Cl. D54—13)

Fig. 1 is a side elevational view of a brake shoe tool embodying my new design;

Fig. 2 is a top plan view thereof;

Fig. 3 is a fragmentary side elevational view in partly opened position of the right end of Fig. 1 on an enlarged scale; and

Fig. 4 is an enlarged end elevational view thereof taken from the right of Fig. 2.

The side not shown is a mirror image of the side shown.

I claim:

The ornamental design for a brake shoe tool, substantially as shown and described.
